ELECTRON DISCHARGE DEVICE AMPLIFIER

Oswald Edward Keall, Chelmsford, England, assignor to Radio Corporation of America, a corporation of Delaware

Application June 6, 1936, Serial No. 83,867
In Great Britain June 21, 1935

5 Claims. (Cl. 179—171)

This invention relates to electron discharge device amplifiers suitable for use for amplifying very low frequencies for example for use in connection with electrocardiographs and like apparatus for recording or audibly reproducing heart beats.

Where amplification of very low frequencies such as heart beat frequencies is required and resistance capacity coupled thermionic valve amplifiers are sought to be used for this purpose the time constants of the circuit must be selected very large and this involves that the amplifier becomes both uneconomical and bulky largely owing to the relatively great size of the condensers required. It is well known that relatively distortionless amplification of very low frequencies and slow transients can be obtained by means of direct coupled amplifiers but the said amplifiers are not easily adapted to mains operation since the potentiometer necessary for selecting the grid and anode voltages for each stage has portions of its winding common to two or more stages so that instability or loss of amplification or both often occurs. Where the phenomena to be studied are of a periodic or repetitive nature resistance capacity coupled amplifiers may be used so long as their time constant corresponds to the period of repetition. If this period is say 5 seconds, the time constant, which is, of course, equal to the product of the resistance and the capacity of the circuit in question, must be equal to 5. In a resistance-capacity coupled amplifier a limit is usually set to the value of resistance which can be used in the output circuit of any stage by the resistance necessarily present in the input circuit of the succeeding stage this resistance being rarely larger than 2 megohms. Accordingly the resistance in the output circuit of a preceding stage in a resistance capacity coupled amplifier can rarely be allowed to exceed half a megohm and for a 5 second time constant this involves the use of a condenser of 10 microfarads—a very large condenser. It is, of course, possible to increase the effective time constant of a stage by the use of de-coupling condensers and resistances, but the provision of such means involves an increase in the voltage of the source from which the anode voltage is to be derived and this again is undesirable from the practical point of view.

The object of the present invention is to meet the above mentioned difficulties and practical disadvantages, and according to the said invention, there is included in the grid circuit of a stage of resistance capacity coupled amplifica-

tion an additional circuit including resistance and capacity in parallel, this additional circuit being in series with the normally provided grid resistance. It should be noted that an essential feature of the invention and one that is very important in practice, is that the additional circuit is provided in a grid circuit as distinct from in an anode circuit for by reason of the location of said additional circuit in this manner any necessity for increase of the potential of the anode potential source is obviated. Were the additional circuit in an anode circuit, the voltage drop thereacross would have to be made good by the anode potential source, and as above stated this is in practice undesirable.

The invention is illustrated in and further explained in connection with the accompanying diagrammatic and graphical drawing of which Fig. 1 shows the circuit of the invention and Figs. 2 and 3 show curves illustrating certain characteristics of the circuit.

Referring to Figure 1 which shows one way of carrying out this invention as applied to a two stage resistance capacity coupled amplifier suitable for use for amplifying slow transients or low frequencies, such as heart beats, input voltage to be amplified is applied at terminals 1 between grid 2 and cathode 3 of a triode 4 whose cathode lead contains the usual automatic bias resistance arrangement represented by the rectangle 5 and 25 whose anode receives operating potential from a source (not shown) through the usual anode resistance 6. In addition the anode-cathode circuit of the valve 4 includes in the order stated 30 and commencing at the anode a coupling condenser 7 a coupling or grid resistance 8, and an additional circuit consisting of a resistance 9 and capacity 10 in parallel the cathode end of this additional circuit 9, 10, being connected to the cathode 3 through the bias resistance arrangement 5. The portion of the anode circuit 35 consisting of the elements 8, 9 and 10 is also connected between the grid 11 and the cathode 12 of the valve 13 in the next stage. With this circuit arrangement it is possible to choose values 40 of the components 7, 8, 9 and 10 in relation to the anode load of valve 4 in such manner that a substantially rectilinear frequency response may be obtained down to a predetermined low frequency, for example, .1 of a cycle per second, 45 and the coupling resistance 8 and coupling condenser 7 may be chosen to have a time constant which is 10 times less than that which they would have were the additional circuit not provided 50 and the said time constant accordingly selected 55

to correspond to the frequency of .1 of a cycle per second.

In a practical example as illustrated in Figure 1 and designed to amplify down to a frequency of .1 of a cycle per second, the coupling condenser 7 was of 2 microfarads, the coupling resistance 8 was of 100,000 ohms, the condenser 10 was of 1 microfarad, the resistance 9 was of 1 megohm, the anode resistance 6 was of 250,000 ohms and the valve 4 was a high impedance triode with an effective impedance of about 100,000 ohms.

It is worthy of note that with the above described circuit arrangement, the results are not achieved at the expense of phase shift. In the particular example above referred to, with the additional circuit provided the phase shift remained between about $\pm 5^\circ$ down to a frequency of about .35 of a cycle per second, the phase shift thereafter rising to about $+25^\circ$ at .1 of a cycle per second and to about $+45^\circ$ at .05 of a cycle per second. These results are shown graphically by the curve A in Figure 2 phase shift in degrees being plotted as ordinated against frequency. For the same circuit but with the additional circuit omitted the phase shift was about $+45^\circ$ at .8 of a cycle per second, dropping as the frequency rose but not falling as low as $+5^\circ$ until the frequency was about 10 cycles per second, the fall being roughly rectilinear. This result is shown graphically by the broken line curve B in Figure 2. The curve C in Figure 2 shows the results obtained with the condenser 10 of 0.1 microfarad, the circuit details being otherwise as for curve A.

As regards frequency response characteristic, with the specifically described embodiment the gain in decibels was within the limits ± 1.5 down to .06 of a cycle per second, and below this frequency the gain dropped off sharply giving a low frequency cut off effect. This is shown graphically by curve D in Figure 3 in which gain in decibels (ordinates) is plotted against frequency. With the same circuit modified however by the omission of the additional circuit, the gain was -22 at .06 of a cycle per second, and rose approximately rectilinearly to about -4 at .7 of a cycle per second, the curve thereafter flattening out. Part of this result is represented by the broken line curve E in Figure 3. With the specifically described embodiment modified by using, in place of a condenser 10 of 1 microfarad a condenser 10 of 0.1 microfarad a curve as shown at F in Figure 3 was obtained. This curve shows a rising characteristic as frequency is reduced from 70 to 7 cycles per second, the curve then remaining level at about $+4$ decibels down to .2 of a cycle per second, thereafter falling approximately rectilinearly to about -6 decibel at .02 of a cycle per second. From the corresponding phase shift curve C of Figure 2 it will be seen that phase shift remains between $\pm 12^\circ$ down to .3 of a cycle per second thereafter rising approximately rectilinearly to $+45^\circ$ at about .065 of a cycle per second. Such an arrangement could be utilized to give increased response at low frequencies or to correct for a loss in low frequency response in some other circuit. It will be appreciated that in order to obtain a large amount of correction the grid coupling resistance should be small as compared to the anode load resistance while the resistance of the additional circuit should be of the same order as, or higher than the anode load resistance. The valves of the grid coupling condenser and the condenser in the additional circuit may then be chosen to

produce a desired correction in a desired part of the frequency spectrum to be handled by the amplifier.

Although the invention has been particularly described in respect to its application to cardiograph amplifiers, it is not limited to such application and may be applied to all amplifiers for operation at very low frequencies. As will now be seen another application which is rendered possible by the nature of the frequency response curves obtainable, is to amplifiers required to cut off sharply at a predetermined low frequency and heavily attenuated frequencies below the said predetermined low frequency. The invention is accordingly applicable to high pass or band pass filters and is very advantageous when so applied as the phase shift remains approximately constant and at a low value at frequencies above the cut off value.

Where the invention is applied to cases where the low frequency cut off effect is required to be made sharp the said cut off effect may be sharpened up by the provision of an inductive element 14 in parallel with the resistance and capacity in the additional circuit. In this connection it will be appreciated that since the circuit will be effective in the manner desired only when the dynamic resistance of the inductance and condenser in the additional circuit approaches the value of the resistance in said circuit, practical considerations will limit the application of embodiments involving an inductance in the additional circuit to amplifiers operating at frequencies considerably higher than the extremely low frequencies numerically specified hereinbefore. Nevertheless the modified circuit wherein an inductance is included in the additional circuit is of fairly wide application, and it will be found of considerable advantage in relatively low frequency amplifiers where a sharp low frequency cut off is required and the obtaining of an approximately constant small phase shift at frequencies above this cut off point is desired.

Having now particularly described and ascertained the nature of my said invention and in what manner the same is to be performed I declare that what I claim is:

1. In a resistance capacity coupled low frequency amplifier adapted to provide substantially rectilinear frequency response down to one tenth of a cycle per second, a first tube having an anode, a cathode and a control electrode and a second tube provided with an anode, a cathode and a control electrode, means for impressing the low frequency signal energy between the grid electrode and cathode of the first tube, means including a resistor element of the order of 250,000 ohms for connecting the anode of the first tube to a source of space current, a coupling condenser of the order of two microfarads directly connected between the anode of the first tube and the grid electrode of the second tube, a connection between the cathode of the first tube and the cathode of the second tube, a grid resistor for said second tube and an additional resistor in series connected between the grid of the second tube and the cathode thereof, said grid resistor being of the order of 100,000 ohms and said additional resistor being of the order of 1 megohm and a condenser shunted across the additional resistor, said condenser being of the order of 1 microfarad.

2. In a resistance capacity coupled low frequency amplifier adapted to provide substantially rectilinear frequency response down to a

- fraction of a cycle per second, a first tube having an anode, a cathode and a grid electrode, and a second tube having anode, cathode and grid electrodes, means for impressing the low frequency energy to be amplified upon the grid electrode of the first tube, a grid circuit for the second tube including a grid resistor in series with a parallel arrangement of a resistance and condenser, a condenser connected directly between the anode of the first tube and the grid electrode of the second, said parallel arrangement of resistance and condenser in the grid circuit of said second tube being proportioned relative to the first named resistance and the coupling condenser so that the latter two have a time constant which is of the order of ten times less than that which they would have were the parallel arrangement not provided whereby frequencies as low as a fraction of a cycle per second may be amplified in said amplifier.
3. In a resistance capacity coupled low frequency amplifier having a sharply defined low frequency cut-off point, a first tube having an anode, a cathode and a grid electrode, a second tube provided with an anode, a cathode and a grid electrode, means for impressing the low frequency energy upon the grid electrode of the first tube, a grid circuit for the second tube including a grid resistor and in series therewith a parallel arrangement of a resistance and condenser, a coupling condenser connected between the anode of the first tube and the grid electrode of the second and means comprising an inductance element connected in parallel with the last named resistance for determining the low frequency cut-off point of the amplifier.
4. In an amplifier circuit, a first electronic tube provided with an anode, a cathode and a grid electrode, external circuits related to said tube electrodes and forming an input circuit and an output circuit for said tube, said tube producing amplified voltage in its output circuit from voltage impressed upon its input circuit, a second electronic tube having an input electrode, means for impressing the output of said first tube upon the input electrode of said second tube comprising a voltage divider connected between the anode and cathode of said first tube, said voltage divider comprising two impedance networks connected in series, said input electrode being connected to the junction of said two impedance networks, the first of said impedance networks comprising a series condenser which causes the impedance of the first network to increase with decreasing frequency thereby tending to reduce the fraction of the original voltage that is fed to the input electrode of the second tube, the second of said two impedance networks comprising a series resistance and in series therewith a combination of impedances permeable to direct current and providing an impedance to alternating current which increases as the frequency decreases over a useful range to such an extent that the voltage division produced by said divider is rendered more uniform over said range of useful frequencies.
5. An arrangement as described in claim 4 wherein said second of said two impedance networks comprises a resistor in series with a second resistor shunted by a condenser.
